UNITED STATES PATENT OFFICE

151,207

DESIGN FOR AN ELECTRIC FLOOR POLISHER

Kenneth C. Atkin, Muskegon, Mich., assignor to
Clarke Sanding Machine Company, Muskegon,
Mich., a corporation of Michigan

Application January 12, 1948, Serial No. 143,667

Term of patent 14 years

(Cl. D9—2)

To all whom it may concern:

Be it known that I, Kenneth C. Atkin, a citizen of the United States, residing at Muskegon, in the county of Muskegon and State of Michigan, have invented a new, original, and ornamental Design for an Electric Floor Polisher, of which the following is a specification, reference being had to the accompanying drawings, forming a part thereof.

In the drawings:

Figure 1 is a front perspective view of an electric floor polisher, showing my new design, and Figure 2 is a back perspective view thereof.

I claim:

The ornamental design for an electric floor polisher, substantially as shown.

KENNETH C. ATKIN.
